UNITED STATES PATENT OFFICE

169,792

COMB

William Sklavenitis, Geneva, Ill.

Application December 29, 1952, Serial No. 22,905

Term of patent 14 years

(Cl. D86—8)

To all whom it may concern:

Be it known that I, William Sklavenitis, a citizen of the United States and a resident of the city of Geneva, in the county of Kane and State of Illinois, have invented a new, original, and ornamental Design for a Comb, of which the following is a specification, reference being had to the accompanying drawing, forming part thereof.

Figure 1 is a front or face view in elevation of a comb, showing my new design;

Figure 2 is a top plan view of the comb showing a row of teeth on each side thereof;

Figure 3 is an end view in elevation of the comb; and,

Figure 4 is a vertical cross-sectional view thereof along the line 4—4 of Figure 1.

I claim:

The ornamental design for a comb, as shown and described.

WILLIAM SKLAVENITIS.
